Primary Examiner — Elizabeth J Oswecki*Assistant Examiner* — Lacey Chey Bowman(74) *Attorney, Agent, or Firm* — Sheppard, Mullin, Richter & Hampton LLP; Xin Xie**CLAIM**

The ornamental design for a camera device as shown and described.

DESCRIPTION

FIG. 1 is a front perspective view of a camera device showing our new design;

FIG. 2 is a front view thereof;

FIG. 3 is a left side view thereof;

FIG. 4 is a right side view thereof;

FIG. 5 is a top plan view thereof;

FIG. 6 is a bottom plan view thereof;

FIG. 7 is a rear view thereof; and,

FIG. 8 is a rear perspective view thereof.

The broken lines represent portions of the camera device that form no part of the claimed design. Any variation in length or thickness of the broken lines is unintentional and all of the broken lines form no part of the claimed design.
